UNITED STATES PATENT OFFICE.

JAMES N. BRYANT, OF SPARTA, TENNESSEE, ASSIGNOR OF ONE-HALF TO
REUBEN T. DRAKE, OF ROCK ISLAND, TENNESSEE.

LAWN-MOWER.

No. 805,900.

Specification of Letters Patent.

Patented Nov. 28, 1905.

Application filed July 8, 1905. Serial No. 269,113.

To all whom it may concern:

Be it known that I, JAMES N. BRYANT, a citizen of the United States, and a resident of Sparta, in the county of White and State of Tennessee, have invented certain new and useful Improvements in Lawn-Mowers, of which the following is a specification.

My invention is an improvement in that class of lawn-mowers in which a reciprocating cutter is employed.

The invention is embodied in the novel features of construction, arrangement, and combination of parts hereinafter described and claimed.

15 In the drawings, Figure 1 is a plan view of the machine. Fig. 2 is a longitudinal section of the same. Fig. 3 is a perspective view of the foot or lower end of the frame of the machine. Fig. 4 is an inverted plan view of the 20 front bearing-roller of the frame. Fig. 5 is a perspective view of the heads of adjacent shafts which are adapted to be coupled, so that the rotary motion of one imparts lateral oscillation to the other. Fig. 6 is a sectional view further illustrating the coupling shown 25 in Fig. 5. Fig. 7 is a cross-section of the longitudinal portion of the frame on the line 77 of Fig. 2, the arch or U-shaped beam and the running-wheels being shown in elevation. 30 Fig. 8 is a perspective view of a portion of the reciprocating cutter. Fig. 9 is a perspective view of a portion of the finger-bar or fixed cutter. Figs. 10 and 11 are different sections of the cutting mechanism. Fig. 12 35 shows a modification of gearing.

The frame of the machine includes a longitudinal portion upon whose front end the cutting mechanism is mounted and an inverted-U arch or beam having laterally-extended 40 journals upon which running-wheels H are mounted. The longitudinal portion of the frame comprises a metal bar A, having a foot-piece a and an upper extended portion a', which is bolted to a wooden bar A', and an 45 upper metal piece A², which is in similar manner bolted to the wooden bar A' and constructed to form bearings for rotary shafts, as will be presently described. The upper end of this casting A² is constructed with a 50 ring for receiving a wooden handle a², by which the machine is guided and propelled. The cutting mechanism comprises a fixed finger-bar C, (see Figs. 2, 9, and 11,) the same being bolted to the foot a of the bar A, and a

reciprocating cutter C', which rests upon the 55 finger-bar C and is secured thereto by means of bolts working in longitudinal slots, as shown in Fig. 1. The sides of the fingers of the bar C and also the sides of the cutters of the bar C' (see Fig. 8) are made concave and 60 beveled, and the ends of both are pointed, as shown. By this means I form a very effective cutting mechanism which is adapted to sever grass with the greatest ease and uniformity.

Reciprocating movement is imparted to the 65 cutter C through the medium of a shaft D, which is pivoted at d in the part a of the frame. (See Figs. 1 and 2.) The upper end of the shaft D is provided with an enlarged head d', (see Figs. 2 and 5,) which is constructed with a vertical slot d². The head d' is practically coupled with the head e of the rotary shaft E, as hereinafter described. The said shaft is journaled in bearings a⁴ a⁵ a⁶, one being attached to the under side of the 75 wooden bar A', another provided in the casting or metal frame-piece A², and the third in a lug pendent from bar A. The head e of the shaft E is provided with a pin e², which is eccentrically located. As shown in Fig. 2, the 80 heads d' and e of the respective shafts D E are placed opposite and in close proximity, so that the pin e² projects into and works in the vertically-elongated slot d² of the head d'. The upper end of the shaft D is supported 85 in a bearing which permits its lateral movement therein. Hence when rotation is imparted to the shaft E corresponding lateral oscillation of the shaft D results, or, in other words, the said shaft D is rocked on its pivot 90 d, and thereby reciprocating movement is imparted to the cutter C'. As indicated in Fig. 1, the lower end of the shaft D is constructed with a toothed segmental head d³, which engages a corresponding rack c, formed on the 95 rear edge of the cutter C'. Thus rotation of the shaft E is converted into oscillating motion of the shaft D, which reciprocates the cutter. I may employ either of two methods for imparting rotation to the shaft E. As 100 shown in Figs. 1 and 2, the upper end of the shaft E is provided with a bevel-pinion e³, which meshes with a bevel-gear F, mounted on the shaft F', having a crank f, the said shaft being provided with bearings in the 105 slotted frame A². While clasping the left-hand portion of the handle a² with one hand, the operator may rotate the gear F by means

of the other hand, and thus reciprocate the cutter as desired. For the purpose of steady-
ing the bevel-gear F, I arrange an antifriction-roller at a' . The other means for im-
parting rotation to the shaft E, and thereby
reciprocating the cutter C', are the following:
A toothed rim or annulus G (see Figs. 1 and
2) is affixed to the inner side of the running-
wheels H, the same being suitably bolted to
the latter, as shown. A shaft I is opera-
tively connected with one of the annular
gears G, and a corresponding shaft I' is simi-
larly connected with the other one—that is to
say, each shaft I I' is provided on its outer
end with a spur-pinion i , which engages one
of the annular gears G, as shown. The inner
end of the shaft I is provided with a bevel-
wheel i' , and the shaft I' is provided with a simi-
lar gear i'' . One of these gears i'' meshes
with a bevel-pinion e^4 on the shaft E, and the
other gear i'' meshes with a corresponding
bevel-pinion e^5 on the shaft E. From this
combination and arrangement of parts it is
apparent that either of the wheels will impart
rotation to the shaft E through the medium
of the connecting horizontal shafts I I' and
that the rotation of the shaft E will be always
in the same direction in consequence of the
arrangement of the bevel-gears i'' i'' to mesh
with the opposite bevel-pinnions e^4 e^5 . It is
apparent that one of the shafts I I' must be
set at a slight angle in order that the handle
and the gears may be coupled in this manner;
but the degree of inclination is not sufficient
to perceptibly affect the operation of the
parts. As shown in Fig. 7, the shafts I I'
have their bearings in a U-shaped arch or
beam A', the same having pendent arms a'' ,
as shown.

It is necessary that provision should be
made for such connection between the wheels
H and the shafts I I' that either wheel may
rotate backward, as when the machine is
turned or run backward. For this purpose I
provide clutches, (see Fig. 7,) the same being
constructed as disks having toothed faces
adapted to engage corresponding clutch-faces
on the inner sides of the pinions or gears i .
The disks i^3 are slideable, but non-rotatable on
the axles I I', pinions i being loosely mounted
thereon. The clutch-disks i^3 are held nor-
mally engaged with the pinions by a spiral
spring, which yields to allow backward rota-
tion, as will be readily understood. The clutch-
disks may be provided with clamping-screws
or other means for holding them out of ac-
tion—that is to say, out of contact with the
pinions i —when it is desired to operate the
cutting mechanism by hand-power alone.

The stub-axles upon which the wheels H
are journaled are made vertically adjustable
in the parallel arms of the U-shaped beam A',
said arms being provided with a series of
holes, as indicated in Fig. 2. By this means

the longitudinal frame of the machine may 65
be set higher or lower as conditions require.

The front bearing-wheel K (see Figs. 1 and
4) is journaled in the curved bar l , which is
secured to the foot a of the frame-bar A by
a bolt, the bar l having a series of holes 70
which permits the wheel K to be adjusted
higher or lower.

In the modification shown in Fig. 12 the
transverse shaft I² is made in one piece in-
stead of being divided, and a single bevel-
gear i' is mounted therein and arranged to
engage pinions e^6 , which are keyed on the
aligned ends of shaft-sections E² E³. The lat-
ter are equivalent to shaft E in Fig. 2, and
one of them is provided with a dish having a
pin e^7 for engaging the slotted head d' of shaft
D, (see Fig. 5,) while the other will in prac-
tice extend up to the handle and there con-
nect with the hand-operated gearing. Clutches
are arranged as required to permit backward 85
rotation.

What I claim is—

1. In a lawn-mower, the combination of a
frame comprising a longitudinal portion and
an inverted-U-shaped beam, or arch, ar- 90
ranged vertical and at right angles to the ver-
tical plane of the longitudinal portion, the two
being secured together at their middle, stub-
axles projecting from the pendent end por-
tions of the beam and running-wheels mount- 95
ed thereon, cutting mechanism arranged upon
the front end of the longitudinal portion and
extending laterally and equally on each side
thereof, and means for operating the said
mechanism, substantially as described. 100

2. In a lawn-mower, the combination, with
a longitudinal frame, cutting mechanism ar-
ranged at the front end of the same and in-
cluding a reciprocating cutter, an oscillating
lever pivoted in the frame and operatively
connected with the reciprocating cutter and
having in its upper end a head provided with
an elongated vertical slot, a rotary shaft in
substantial alinement with the oscillating le-
ver, and having an eccentric pin which works
in the aforesaid slot, and means for operating
the rotary shaft substantially as described. 105

3. In a lawn-mower, the combination, with
a longitudinal frame comprising a bar and in-
verted-U-shaped transverse beam having pend- 115
ent arms carrying stub-axles, running-wheels
mounted on such axles, and cutting mech-
anism arranged at the front of the frame, an os-
cillating lever for operating the reciprocating
cutter, a rotary shaft operatively connected
with the oscillating lever, transverse shafts
whose inner ends are geared with such rotary
shaft, internal toothed gears secured to the
running-wheels, and supplemental gearing for
operatively connecting the transverse shaft 120
therewith, substantially as described.

4. In a lawn-mower, the combination, with
a longitudinal frame and an inverted-U-shaped

beam secured together at their middle, axles secured to the pendent arms of the beam, running-wheels mounted on such axles, reciprocating cutting mechanism arranged at the front 5 of the frame, an oscillating lever for imparting reciprocation to the cutter, a rotary shaft operatively connected with the oscillating lever and provided with bevel-pinions arranged opposite and spaced apart, transverse shafts I, I', geared with the respective pinions and operatively connected with the running-wheels whereby rotation is imparted as the machine 10 advances, substantially as described.

5. In a lawn-mower, the combination, of a longitudinal frame comprising a practically 15

straight bar and an inverted-U-shaped beam the two being secured together at the middle of the upper side of the arch, axles secured to the pendent arms of the beam and adapted for vertical adjustment thereon, running-wheels 20 mounted on said axles, a reciprocating cutter arranged at the front of the frame, and an oscillating lever and rotary axles connected and arranged for imparting reciprocation thereto, substantially as described.
